CLAIM

The ornamental design for a sterilization device, as shown and described.

DESCRIPTION

FIG. 1 is a bottom, front, right perspective view of a sterilization device showing our new design;

FIG. 2 is top, rear, left perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a top, rear, left perspective view of the sterilization device of FIG. 1, shown in condition of use.

The broken lines in the drawings depict portions of the sterilization device that form no part of the claimed design. The broken lines showing a cord and bracket in FIG. 9 depict environmental structure that forms no part of the claimed design. All broken lines form no part of the claimed design.

1 Claim, 9 Drawing Sheets
